UNITED STATES PATENT OFFICE.

PAUL LOUIS JOSEPH MIGUET, OF ST.-JULIEN-DE-MAURIENNE, FRANCE, ASSIGNOR TO
SOCIÉTÉ ELECTROMÉTALLURGIQUE DE MONTRICHER, OF ST.-JULIEN-DE-MAURIENNE, FRANCE.

FEEDING APPARATUS FOR ELECTRIC FURNACES.

Original application filed July 8, 1926, Serial No. 121,189, and in France November 4, 1925. Divided and this application filed November 17, 1927. Serial No. 234,007.

This specification is a division of the invention in the Process of electrothermic reduction and the electric furnace for carrying out such process described and 5 claimed in my co-pending application for Letters Patent of the United States of America, filed July 8, 1926, and bearing Serial No. 121,189.

According to this process, the charge is 10 formed by methodic heterogeneous mixtures. The apparent complexity of a feed by means of layers alternately provided with and not provided with carbonaceous material may raise objections especially for units 15 of high power. In order to avoid these objections, a mechanical feeding of the conducting mixtures and above all of the additions is necessary. Concerning these latter it is not obvious for instance, how 3,000 20 kilogs. of iron ores and 360 kilogs. of limestone are to be fed in with a shovel with the speed and regularity necessary for a uniform spreading out of the current and for the separation of the material to be reduced, 25 even by an exaggerated number of workmen.

Objections do not appear with sufficiently 30 important furnaces to justify the installation of a suitable hopper apparatus, because independently of facility of separate feeding, the possibility of correcting the production by appropriate modification of the 35 composition of the layers provided with carbonaceous material without taking care of the mass of the fusion mixtures of the 40 furnace, gives such a simplicity to the process of manufacture that even furnace men the most accustomed to the old method would not return to the former working condition 45 of furnaces with homogeneous fusion mixtures.

The present invention has for its object 45 means for mechanical feeding of the materials into a furnace especially when the above mentioned process is applied.

The invention will be described with reference to the accompanying drawings:

Figs. 1 and 2 are respectively a vertical 50 section and a plan of a feeding arrangement.

Figures 1 and 2 show respectively a vertical section and plan of said arrangement

comprising an annular electric furnace arranged concentrically with the electrode.

The vertical walls 2 extend upwards to 55 the level of the mixing platform 3 and have an inclined bottom 4 prolonged, at each space between two flexible connections *v* connecting two plates *x*, by a feed chute 5 opening out from the chambers 7 and 9 in 60 the hopper respectively through a horizontal shutter 6 and a vertical counterweighted shutter 8. The hopper is divided into chambers 7 containing the additions and feed chambers 9 containing the conduction 65 mixtures, the vertical shutters are each provided with a separate operating lever 10 allowing for the feeding of the conducting mixture at any point of the annular furnace requiring making up and the shutters 6 are all connected through cranks 11 to a transmission Cardan shaft 12 driven through a toothed sector 13 and a worm 14 operated by a single crank 15 being operated at suitable times immediately after the first tapping and the others 8 at half hourly intervals, the additions may be fed uniformly 70 at one time if required.

The hopper is preferably metallic and it is obvious that the arrangement of the 80 chambers as well as that of their discharge means, may be modified according to the kind of furnace to which the invention is applied.

What I claim as my invention and desire 85 to protect by Letters Patent is:—

A feeding apparatus for an electric furnace said apparatus having in combination, a feed hopper, partitions dividing said hopper into compartments, arranged in groups 90 the compartment of each of said groups containing the ones conducting mixtures and the others additions of nonconducting material, a shutter for controlling the discharge of each of said compartments means 95 for ensuring the individual opening of the shutters corresponding to the compartments of the conducting mixtures, means for ensuring simultaneously the opening of the shutters corresponding to the compartments 100 of the additions and a common feed chute for every group of compartments.

In witness whereof I affix my signature.

PAUL LOUIS JOSEPH MIGUET.
